Patented Mar. 26, 1918.

UNITED STATES PATENT OFFICE.

DAVID TOWNSEND SHARPLES, OF WEST CHESTER, PENNSYLVANIA.

TEAT-CUP.

1,260,466.

Specification of Letters Patent. Patented Mar. 26, 1918.

Application filed May 10, 1917. Serial No. 167,663.

To all whom it may concern:

Be it known that I, DAVID TOWNSEND SHARPLES, a citizen of the United States, residing at West Chester, in the county of 5 Chester and State of Pennsylvania, have invented certain Improvements in Teat-Cups, of which the following is a specification.

My invention is a teat cup having improved means for frictionally engaging the 10 teat, to hold the cup in the desired operative position while permitting it to be removed with ease when desired. My improved means are characterized by the use 15 of flexible devices within the cup adapted for frictionally engaging the teat to hold the cup firmly thereon and adapted for being deflected from their normal engagement so as to permit the removal of the cup readily when desired.

20 The nature and characteristic features of my improvements are fully disclosed in the following description and the accompanying drawings in illustration thereof.

In the drawings, Figure 1 is a longitudinal sectional view of a teat cup embodying my invention; Fig. 2 is a plan view of a detached flexible ring used therein; Fig. 3 is a broken longitudinal sectional view of features of the construction shown in Fig. 1 30 represented on an enlarged scale in the position in use; Fig. 4 is a sectional view taken on the line 4—4 of Fig. 3 showing the relation of features of the mechanism in the operation of removing the cup; Fig. 5 is a longitudinal sectional view of a part of a teat cup embodying a modified construction 35 of my invention with the parts in the relation occupied in use; Fig. 6 is a longitudinal sectional view of a part of a teat cup embodying a further modified construction of 40 my invention with the parts in the relation occupied in use; Fig. 7 is a plan view of a detached ring used in the construction shown in Fig. 6, and Fig. 8 is a sectional view on the line 8—8 of Fig. 6 showing the relation of the fingers to the teat in the 45 operation of removing the cup.

My improved teat cup comprises a shell body 1 having a detachable section 1' connected and disconnected with relation thereto by the coöperative threads 1^a and 1^b, the body of the shell being provided with the internal flange 1^c and with the nipples 1^d and 1^e. A rubber tube 2, having the

tapered bottom 2^a with the slit 2^b therein, is 55 provided at its top with the exterior annulus 2^c which rests on the flange 1^c.

As illustrated in Figs. 1 to 4 inclusive, a ring 3 is placed in the top of the section or sleeve 1' against the shoulder 1^c thereof; 60 soft rubber rings 4, containing peripheral metal stiffening rings 4^a and radial slits 4^b forming the prehensile fingers 4^c, are placed in the sleeve 1' against the ring 3 with their respective slits staggered; a second ring 3 is placed in the sleeve against the bottom ring 4; additional rings 4 are placed in the sleeve against the second ring 3; and a ring 3' is placed in the sleeve against the last named ring 4, the ring 3' 70 being firmly engaged with the annulus 2^c by screwing down the sleeve 1' upon the body 1 and the rings 3 and 4 being thereby held in place.

The animal's teat 5, being entered through 75 the top of the teat cup and passing through the rings 4, deflects the fingers or sections 4^c downwardly and outwardly, with the result that such fingers or segments are not only frictionally engaged with the teat but 80 are so disposed as to be placed under longitudinal compression, acting as tentacles or struts against the surface of the teat to hold the cups thereon firmly in the proper position.

85 While these fingers or sections act strongly when in normally deflected positions to hold the cup upon the teat, it will be understood that by twisting or turning the cup the torsional action deflects the fingers or tentacles 90 laterally as shown in Fig. 4 and permits the cup to be drawn off the teat without difficulty.

As illustrated in Fig. 5, rings 4 may be placed directly against the shoulder or seat 95 1^c in the top of the cup and held in place by rings 3, when the greater force applied to the fingers or tentacles 4^c, due to the reduced number of rings 4 used, will, through tending to buckle the fingers, hold 100 the teat cup in place satisfactorily.

As illustrated in Figs. 6, 7, and 8, the sleeve 1' may be provided with a ring 6 clamped between the shoulder 1^c and a ring 3 and with a second ring 6 clamped 105 between rings 3, the rings 6 having peripheral stiffening rings 6^a and radial fingers 6^b of flexible character.

These prehensile fingers, upon the insertion of the teat 5 through the top of the cup and through the rings, are deflected downwardly and outwardly, as illustrated in Fig. 6, so that they are disposed angularly to the teat, similarly to the elements of a cone. Therefore the weight of the cup is carried longitudinally through these fingers to the teat, the fingers acting as struts to resist the tendency of the cup to fall off or move from its correct position. In this, as in the previous forms, the cup is removed by turning it upon the teat and deflecting the fingers 6 to the position shown in Fig. 8.

15 It will be understood that while soft rubber is well adapted for providing the annular brush or ring having tentacles for grasping the teat, any suitable material, as bristles, may be substituted for the rubber 20 tentacles.

Having described my invention, I claim:

1. A teat cup having independently movable flexible members adapted to be deflected by the insertion of the teat into the cup and to frictionally engage the teat to hold the cup thereon.
2. A teat cup having flexible tentacles therein adapted to be deflected by the insertion of the teat into the cup and to grasp the teat to hold the cup thereon.
3. A teat cup having flexible interior members adapted to be deflected downwardly and outwardly by the insertion of the teat in said cup, to frictionally engage

the teat to hold said cup thereon, and to be 35 deflected laterally by turning the cup so as to permit its ready detachment from the teat.

4. A teat cup having an interior brush like device comprising a ring provided with 40 inwardly projecting flexible members adapted to be deflected downwardly and outwardly by the insertion of the teat into said cup and to grasp the teat so as to hold said cup thereon, said members being adapted for 45 lateral deflection by turning said cup.

5. A teat cup having therein a rubber ring containing radial slots forming segments adapted for grasping a teat inserted in said cup and movable laterally to permit the release of said teat from said cup.

6. A teat cup comprising a shell containing, in the upper end thereof, a plurality of rings having flexible members, the separations between the members of the respective 55 rings being staggered.

7. A teat cup comprising a shell having separable sections, one of said sections being provided with an interior flange, a flexible tube engaging said flange, and means 60 comprising a ring and tentacles disposed above said tube for grasping a teat inserted in said cup, the other of said sections having a shoulder for pressing said means against said tube.

In testimony whereof I have hereunto set my name this 8th day of May, 1917.

DAVID TOWNSEND SHARPLES.
